INVENTOR:

JOSEPH WALTER KAVETZKI,
By Arthur E. Paige

UNITED STATES PATENT OFFICE.

JOSEPH WALTER KAVETZKI, OF PHILADELPHIA, PENNSYLVANIA.

BREAST-STRAP.

SPECIFICATION forming part of Letters Patent No. 744,967, dated November 24, 1903.

Application filed July 7, 1903. Serial No. 164,539. (No model.)

To all whom it may concern:

Be it known that I, JOSEPH WALTER KAVETZKI, of Philadelphia, in the State of Pennsylvania, have invented certain new and useful Improvements in Breast-Straps, whereof the following is a specification, reference being had to the accompanying drawings.

My invention relates to double-team harness, and particularly to the means for connecting a wagon-pole with the collars of the team. Various forms of devices have been employed for the purpose specified; but so far as I am aware it is characteristic of all of them that their several members are inseparably connected, so that if one member is broken it is necessary to practically remake the device to repair it.

It is the object of my invention to provide a device of the character described comprising a central strap provided at its opposite ends with chains and snap-hooks detachably connected therewith, so that if any one of said members is broken it may be readily replaced by an unskilled operator, and in order to secure the most efficient use of my improved devices I find it desirable to provide each of them with a wearing-plate for engagement with the ring of the pole-chain and to make them right and left handed in the respect that the length of the strap extending from said wearing-plate to its point of attachment to the collar on the side adjoining the pole is less than the length of said strap extending from said wearing-plate to its point of attachment to the collar on the side distant from the pole. It is also characteristic of my device that means are provided to retain said wearing-plate in its eccentric position with respect to the length of the strap.

My invention comprehends the various novel features of construction and arrangement hereinafter more definitely specified and claimed.

In the drawings, Figure I is a front edge view of a strap for the right-hand member of the team. Fig. II is a face view of the portion of the strap shown at the right-hand side of Fig. I. Fig. III is an outside face view of the portion of the strap shown at the left-hand side of Fig. I. Fig. IV is a sectional view taken on the line IV-IV in Fig. I.

In said figures the central body portion of

the device is preferably made of a three-ply leather strap 1, provided at its opposite ends with metal eye-clips 2 3, whose flat plate-shanks 4 5 are respectively secured to said strap 1 by rivets 6 7. Intermediate of said clips 2 3 said strap 1 is provided with the wearing-plate 8, which is retained in the eccentric position shown in Fig. I by engagement beneath the shank 4 of the clip 2 adjoining its rivet 6. Said clip 2 is provided with two open chain-links 10 11, the former being directly engaged with the eye of said clip 2 and the latter being engaged with said link 10 and with the aperture 13 in the shank 14 of the snap-hook 15. Similarly the clip 3 is provided with two open links 16 17, the former being directly engaged with the eye of said clip 3 and the latter being engaged with said link 16 and with the aperture 19 in the shank 20 of the snap-hook 21. It is to be noted that said snap-hooks 15 21 are connected with their respective eye-clips 2 3 by chains, each consisting of an even number of links, so that said hooks are maintained pointing outwardly, which is desirable to facilitate their manual engagement and disengagement with respect to the fastening-rings 22 23, carried by the collar.

It is to be understood that I do not desire to limit myself to the precise construction hereinbefore described, as it is obvious that various modifications may be made therein without departing from the essential features of my invention.

I claim—

1. In a breast-strap, the combination with a central body of leather; of metal eye-clips fitted to the opposite ends of said body and comprising shanks embracing the opposite sides of said body; rivets entered through said shanks and said body, securing said clips in stationary relation thereto; a wearing-plate embracing said body and disposed in eccentric relation to its length; the shank of one of said clips overhanging said wearing-plate and securing the latter in stationary relation to said body; chains, each consisting of an even number of open links, detachably connected with said eye-clips; and, snap-hooks respectively detachably connected with the free ends of said chains, substantially as set forth.

2. In a breast-strap, the combination with a central body of leather provided with terminal eye-clips; of chains each consisting of an even number of links respectively detachably connected with said clips; snap-hooks respectively detachably connected with the free ends of said chains; a metal wearing-plate embracing said leather body, in eccentric relation thereto; and, means, connected with one of said eyepieces, engaging said wearing-plate and securing the same in stationary relation to said body, substantially as set forth.
5. In a breast-strap, the combination with a central body of leather, provided with a wearing-plate intermediate of its ends; of eye-clips fitted to the ends of said body; rivets entered through said clips and said body; one of said clips engaging said wearing-plate; and, chains respectively detachably connect-

- 15.

ed with said clips, and each comprising two open links and a snap-hook, detachably connected with each other, substantially as set forth.

4. In a breast-strap, the combination with a leather body; of a wearing-plate mounted on said body intermediate of its ends; eye-clips attached to the ends of said body; one of said clips being engaged with said wearing-plate; and snap-hooks provided with means detachably connecting them with the respective eye-clips, substantially as set forth.

In testimony whereof I have hereunto signed my name, at Philadelphia, in the State of Pennsylvania, this 6th day of July, 1903.

JOSEPH WALTER KAVETZKI.
